(Cl. D57—1)

To all whom it may concern:

Be it known that we, Isidor Fishberger, Sam Levine, and Hyman Weinstein, all citizens of the United States of America, and residents of the city and State of New York, have invented a new, original, and ornamental Design for a Spectacle Frame or Similar Article, of which the following is a specification, reference being had to the accompanying drawing forming a part hereof, in which

Figure 1 is a front elevational view of a spec-

tacle frame or similar article, showing our new design; and

Figure 2 is a top view thereof, the essential features residing in the part shown in full lines.

We claim:

The ornamental design for a spectacle frame or similar article, as shown and described.
